UNITED STATES PATENT OFFICE.

FREDERICK HEATH, OF TACOMA, WASHINGTON.

PILASTER CONSTRUCTION.

Application filed May 1, 1920. Serial No. 378,056.

To all whom it may concern:

Be it known that I, FREDERICK HEATH, a citizen of the United States, residing at Tacoma, in the county of Pierce and State of Washington, have invented certain new and useful Improvements in a Pilaster Construction, of which the following is a specification.

This invention relates in general to building construction and more particularly to hollow tile structures, in which the walls are provided at intervals with pilasters, chimney breasts and buttresses.

Pilasters and buttresses sometimes are utilized in wall construction merely for architectural effects, but more often, they are employed to reinforce the wall for strengthening purposes and for the purpose of serving as load carrying pillars.

Unless the pilaster or buttress structure is securely interbonded with the wall structure so as to become in effect, an integral part thereof, its effectiveness as a reinforcement and as a load-carrying member in conjunction with the wall is insufficient and the purpose for which the pilaster or buttress was designed is not attained. Prior to my invention, the inability to satisfactorily and firmly interbond the pilaster or buttress and wall structures together, has mitigated against the employment of hollow tile walls where pilaster and buttress constructions were required.

One of the primary objects of my present invention is to provide a pilaster or buttress construction which shall be so interwoven and interbonded with the body of the wall itself that it becomes an integral part of the wall and serves to strengthen and reinforce the wall proper and at the same time, provides a load-carrying pillar of maximum strength in which the weight or load to be carried is distributed between the wall body and the pilaster or buttress pillar.

Another object of my invention is to provide a block particularly adapted for this pilaster and buttress construction and which is capable of use in the construction of pilasters and buttresses of various standard dimensions, such for instance as 8 inch, 12 inch, 16 inch, 20 inch, and even larger widths, if desired, and in depths of 4 inch gradations.

In order to facilitate an understanding of my invention, I have illustrated on the accompanying drawings, preferred embodiments

thereof, from an inspection of which when considered in connection with the following description, my invention and many of its inherent advantages should be readily understood by those skilled in the art. 60

Referring to the drawings:

Fig. 1 is a perspective view, partially in section, of a pilaster construction embodying my invention;

Fig. 2 is a perspective view of my improved pilaster block; 65

Fig. 3 is a perspective view of a larger size pilaster construction in which the same pilaster block is utilized;

Fig. 4 is a fragmentary plan view of one 70 course of a pilaster construction, such as is shown in Fig. 1;

Fig. 5 is a similar view of the next superposed course;

Fig. 6 is a similar view, showing one course 75 of the pilaster construction illustrated in Fig. 3;

Fig. 7 is a similar view of the next superposed course;

Fig. 8 is a fragmentary perspective view 80 of a pilaster construction incorporated in a thicker wall than that disclosed in Figs. 1 and 3;

Fig. 9 is a plan view of the bottom course shown in Fig. 8; 85

Fig. 10 is a plan view of the next superposed course in Fig. 8;

Fig. 11 is a view similar to Fig. 8 showing the construction of a wider pilaster;

Fig. 12 is a fragmentary plan view of the 90 lower course shown in Fig. 11;

Fig. 13 is a similar view of the next superposed course shown in Fig. 11;

Fig. 14 is a view similar to Fig. 11 showing the construction of a still wider pilaster, 95 and;

Fig. 15 is a similar view showing my invention embodied in a chimney breast structure.

Referring now the drawings more in detail and particularly to Figs. 1 and 2 thereof, it will be observed that my improved pilaster block, best shown in Fig. 2, is substantially rectangular in shape, its height being substantially equal to the height of the wall blocks with which it is employed and its width being slightly less than one half its length. Obviously, the dimensions of the block may be varied without departure from the essence of the invention, but for stand- 100
105
110

ard purposes, I prefer to make my block in, its utility, thus causing a large amount of spoilage.

	Inches.
5 Height	5 $\frac{1}{2}$
Length	8
Width	3 $\frac{7}{8}$

With these dimensions, it will be manifest that two blocks laid side by side with a $\frac{1}{4}$ inch space between them will just equal in aggregate width the length of one of my blocks.

The pilaster block shown in Fig. 2 and indicated generally by reference character 15, is made of clay of suitable composition, which is formed by machinery into the requisite shape and is then burned or fired in the customary manner. The completed block comprises a series of vertically disposed webs and voids. Centrally and extending transversely of the block, I form a void in the shape of a narrow slot 16, which is preferably $\frac{1}{4}$ of an inch wide, or in other words, it is equal to the space between two blocks laid parallel when their longitudinal outside faces are aligned with the ends of a superposed or subjacent similar block. At each side of this central slot the block is formed to provide a plurality, preferably four vertically disposed parallel voids 17 separated by longitudinal and transverse vertical webs, as shown. It will be observed that the walls surrounding each of these voids are all of substantially uniform thickness, which not only facilitates uniform drying and firing of the block without warping or distortion, but this uniform dimension also enables the blocks to be superposed with their webs and voids in absolute vertical alignment when the blocks are disposed with their longitudinal axes at right angles to each other.

The walls between the various voids are known as webs while those forming the side and end walls of the block are known as shells. The shell and web walls are, as previously mentioned, all of substantially uniform thickness, with the exception, however, of the shell portions intermediate the ends of the block forming the end walls of the void or slot 16. At these points the thickness of the shell is materially diminished so as to provide a weakened line of cleavage along which the blocks may be readily broken with a trowel to produce half blocks for use, as will later appear.

I am aware that tile blocks have, prior to my invention, been provided with V-shaped grooves or kerfs to facilitate breakage along a predetermined line, but I have found that grooves or kerfs so shaped result in a fracture or crack along this line in the wall of the tile when it is being burned. Such a fracture renders the tile valueless as a facing tile and in many cases entirely destroys

It will be observed that the outer edges of the slot 16 in my tile are full width, producing a flat surface as distinguished from a sharp edge, and leaving a uniform thickness of material between the slot and the outer faces of the shell. In drying, the uniformly thick shell at the sides of the slot dries evenly without distortion so that no cracking or fracture occurs.

This method of weakening the shell walls from the inside enables them to be readily split or broken while at the same time, it leaves the exterior of the block smooth and unscored so that it is capable of use for facing purposes.

In Fig. 1, I have illustrated the construction of a pilaster, 4 inches deep and 8 inches wide, in conjunction with an 8 inch wall. The wall blocks, indicated generally by reference character 18, are of the approved type, disclosed in my prior Patent No. 1,215,149, granted February 6, 1917, and in the 8 inch wall illustrated, these blocks are laid in courses directly over each other but with the joints between adjacent horizontal blocks, broken in adjacent courses, as is customary in laying walls of this character. In order to incorporate with and securely bond to this wall a pilaster construction embodying my invention, I proceed as follows: An 8 inch pilaster being desired, I lay adjacent the face of the wall at the place where the pilaster is to be, one of my pilaster blocks, which is disposed parallel with the face of the wall, as shown in Fig. 4, this pilaster block in Figs. 1 and 4 being indicated by reference character 19. Since the block is not quite 4 inches wide, I point with mortar the edges of the space between the block and the face of the wall, so that the outer face of the block is disposed just the requisite 4 inches from the face of the wall. This first pilaster block is, of course, laid simultaneously with the laying of the first course of wall block.

In the building of the second course, the pilaster blocks are preferably laid first and instead of being parallel with the wall, I lay two blocks transversely of the wall with their outer faces in vertical alignment with the outer faces of the block 19, these two blocks being indicated in Figs. 1 and 5 by reference character 21. It will be manifest that with the outer faces of the blocks in vertical alignment, there is a space left between them, equal to the width of the slot 16 in the subjacent block 19, and this space is left open to provide a dead air space, except at its margins, where it is filled for a short distance with mortar 22. With the blocks thus positioned, all of the voids of the outer half of the two blocks 21 are in absolute vertical alignment with the correspond-

130

ing voids 17 in the subjacent block 19 and all of the vertical webs and shell walls surrounding these voids are in absolute vertical alignment in the two courses. This alignment insures the maximum load-carrying or crushing strength in the pilaster blocks.

The space within the wall body at the rear ends of the two blocks 21 is now filled by placing therein longitudinally of the 10 wall, a third pilaster block, which is indicated by reference character 23. The inner face of this block is thus disposed flush with the other face of the wall and since it overlies the joint between these subjacent 15 wall blocks 18, it serves to break the joint and bond these blocks together. It is understood, of course, that a layer of mortar is placed between the horizontal courses of both the wall and pilaster blocks. In the 20 laying of the third course, the arrangement carried out in course No. 1 is followed and in the fourth course, the arrangement of course No 2, and so on, the full height of the wall, with the result that the pilaster 25 blocks of each course are disposed at right angles to the blocks of the next subjacent and next superposed courses and are alternated with the wall blocks of the wall body proper so that the whole structure is firmly 30 interbonded and bound into an integral construction in which the vertical webs of the superposed pilaster blocks are in vertical alignment so as to provide a maximum load-carrying strength in the construction.

Furthermore, since those portions of the 35 pilaster blocks which are disposed within the planes of the wall proper lie between the flat horizontal faces of the underlying and overlying wall blocks, it will be manifest that a strong and firmly interbonded structure is produced. The mortar between the 40 courses also serves to augment the bonding and it will be apparent that the ends of the web and shell walls present an aggregate surface of considerable area for mortar contact so that very little if any mortar falls through the open ended voids.

Should it be desired to provide a 12 inch 45 pilaster in a wall of this thickness, the method disclosed in Figs. 3, 6 and 7 is followed. In the lower course, I again lay a pilaster block along the outer face of the wall and parallel therewith, this block being indicated by reference character 24. At one end, 50 however, I add another block, 25, arranged transversely of the wall with its outer end flush with the outer face of the block 24, as shown in Figs. 3 and 6. The space at the inner end of the block 25 within the wall 55 body is filled by half block 26, which is obtained by cutting one of the blocks 15 transversely through the center in the plane of the slot 16 in the manner previously explained. In the next superposed course, 60 the order is reversed, the longitudinal block

being placed to overlie one half of each of the blocks 24 and 25, this block being now numbered 27 and, at the left hand end of the block 27, I place in transverse position, block 28, and at the inner end of this block, 70 another half block 29. The wall blocks 18 are laid with relation to the pilaster blocks in the manner shown in Figs. 3, 6 and 7, from which it will be observed that the joints of both the pilaster blocks and the 75 wall blocks are broken in each alternate course, thus securing the maximum strength and, again in this structure, the maximum load-carrying strength is secured by having all of the vertical walls of the pilaster blocks 80 in vertical alignment.

The 8 inch pilaster in conjunction with a 12 inch wall is illustrated in Figs. 8, 9 and 10. The 12 inch thickness of the wall body is obtained by using in conjunction with the 85 wall blocks 18, half blocks, which are indicated by reference character 31, the method of laying these blocks being fully described in my prior patent above mentioned, but from the illustrations herein, it will be 90 apparent that the blocks 18 and 31 are arranged on opposite sides of the wall in alternate courses.

The first course of the pilaster structure is again started by laying a block parallel with 95 the outer face of the wall, as indicated by reference character 32, and in the next course two blocks are laid transversely of the wall, as indicated by reference character 33, these blocks being arranged with their webs and 100 voids in vertical alignment with the webs and voids of the block 32, as previously described. In this instance, the employment of a longitudinally extending block at the rear of the blocks 33 as illustrated in Fig. 1 105 is unnecessary, as is also the employment of a half block such as 26 illustrated in Fig. 3, since the alternation of the blocks 18 and 31 completely take care of the wall body structure and provide a sturdy and firmly inter- 110 bonded pilaster and wall construction by simply alternating the position of the pilaster blocks in successive courses.

A 12 inch pilaster in conjunction with a 12 inch wall is secured by laying the blocks 115 as illustrated in Figs. 11 to 13 inclusive, from which it will be observed that the first course comprises a longitudinal pilaster block 34 with a transverse block 35 at one end thereof, the space at the rear of the 120 block 35 being filled by a half block 36. In the next course where the half wall block 31 appears at the outside, the longitudinal block now indicated by 37 overlies the blocks 34 and 35 while the transverse 125 block 38 overlies the block 34 and the subjacent block 18, and just reaches to the block 18 of this course as shown in Fig. 13 so that no half block is necessary.

In this instance also, the joints in succes- 130

sive courses of both the wall blocks and the pilaster blocks are broken and the vertical webs and shells of the pilaster blocks are disposed in vertical alignment, thus insuring maximum load-carrying strength.

In Fig. 14, I have illustrated as a further embodiment of my invention, a 20 inch pilaster in conjunction with a 12 inch wall. The wall proper in this instance consists of the tile 18 and the half tile 31, as previously explained, but in the first course where the half tile 31 appears on the outside of the wall, the pilaster is begun before the half tile 31 are laid. The pilaster structure in this instance comprises in the first course the pilaster blocks 41 and 42 laid transversely of the wall, their inner ends being spaced half an inch from the tile 18 so that these blocks are disposed within the longitudinal planes of the half tiles 31, the ends of which when these tiles are laid, abut against the blocks 41 and 42 as shown. Between the pilaster blocks is interposed one of the building tile 18, which is substantially 12 inches in length, and together with the pilaster blocks 41 and 42 is bonded into the wall structure itself.

In the next course, the wall proper consists of the tile 18 and 31, and the pilaster projection is composed of two pilaster blocks 43 and 44 laid longitudinally, and a half block 45 interposed between them. The third course is a repetition of the first, and alternate courses throughout the height of the structure are duplicates.

I have shown for purposes of illustration merely a shorter tile 46 interposed between the tiles 18 in the inner courses of the construction to strengthen the construction by a desirable breakage of joints, but obviously, standard length tile may be employed in the entire structure with practically as good results. It will be observed that in this embodiment of the invention also the webs and voids of the superposed pilaster blocks are disposed in vertical alignment and that the pilaster structure is in reality a part of the wall structure, into which it is firmly bonded so that it presents a completed structure having maximum load-carrying ability.

In Fig. 15, I have illustrated my invention as embodied in a chimney breast construction which, in all essential respects, is similar to the 20-inch pilaster construction just described and illustrated in Fig. 14, except that in chimney breast construction, provision is made for a flue lining around which the tiles and blocks are laid, as will now be described.

The flue lining, which is customarily made of fire clay, is illustrated in the present instance as being approximately 12 inches square, the lining being designated by reference character 40. In laying the

first course, the bottom section of the flue lining is first placed in position and the double tile 18 abutted against this lining, which is so positioned that its outer face is flush with the outer face of the half tile 31, which is spaced from the flue lining by the inter-position of a pilaster block 41. The tile 18 obviously projects inwardly beyond the inner face of the flue lining so that a space 4 inches wide and 12 inches long at the inner side of the flue lining between the blocks 18 is left, and this space is then filled with a half tile 31.

The pilaster block 42 is similarly disposed at the opposite side of the flue lining between this lining and the half tile 31 and the outer face of the flue lining is covered by a pilaster block 47 laid lengthwise between the blocks 41 and 42.

In the next course, the tile 18 is laid on the outside and is therefore, disposed in alignment with the flue lining, the inner face being covered by the half tile 31 as illustrated and the outer face by two pilaster blocks 43 and 44 and an interposed half block 45, as shown in the drawings. The superposed courses alternate in arrangement so that the tile and blocks are all firmly bonded together into a strong, durable construction surrounding and enclosing the vertically disposed flue lining.

From the foregoing illustrations, it will be manifest that my invention may be embodied in not only 8, 12, 16 and 20 inch pilaster constructions, but also in larger multiples of four, by arranging the blocks in the general manner indicated in connection with the forms herein illustrated. In every instance, however, the blocks are so arranged that their webs are in vertical alignment and the pilaster blocks are firmly interbonded and bound with the wall blocks to insure maximum strength of the structure.

It is believed that my invention and the manner of constructing the same and many of its inherent advantages will be fully understood and appreciated from the foregoing without further description, but it should be obvious that various modifications in the structural details illustrated and described may be referred to without departing from the essence of the invention, as set forth in the following claims.

I claim—

1. A pilaster construction, comprising wall blocks and pilaster blocks arranged in interbonding relation in superposed courses, the width of each pilaster block being slightly less than one half its length, one of said courses including a pilaster block disposed parallel with and entirely outside of the wall face and the next superposed course including a pilaster block disposed at right angles to and overlapping said subjacent block and also overlapping a wall block.

within the wall body to securely bond the wall and pilaster together.

2. A pilaster construction, comprising superposed courses, each consisting of wall blocks and pilaster blocks, one course including a pilaster block disposed parallel with and outside the wall face, and the next superposed course including a pilaster block arranged transversely of the wall and having a portion thereof disposed inside the face of the wall and supported by a subjacent wall block, and a portion disposed outside said wall face and supported upon said subjacent pilaster block whereby said pilaster and wall body are bonded together.

3. A pilaster construction, consisting of wall blocks and pilaster blocks arranged in courses in interbonded relation, said pilaster blocks being equal in height to the wall blocks and of a width slightly less than one half their length, each pilaster block being provided with vertically disposed voids separated by vertically disposed webs, one of said voids being relatively narrow and extending transversely of the block substantially centrally thereof, the pilaster blocks in the superposed courses being disposed alternately parallel with and perpendicular to the face of the wall with all of the webs and voids outside the wall face in perpendicular alignment, the pilaster blocks disposed perpendicular to the wall face being supported at their inner ends upon the wall blocks within the wall body so that said wall blocks and pilaster blocks are interbondingly bonded together.

4. In a construction of the character described, in combination, wall blocks arranged in courses, each block having parallel intermediate webs and three longitudinal voids, and hollow column blocks having webs and shells and being of the same height as said three void blocks and of a length equal to the width of the three void blocks, and arranged in courses parallel

with the direction of the wall blocks in one course and transversely thereof in another course and closing the ends of the adjacent voids of the wall blocks in each course and overlapping a subjacent block, the web and shell members of the column blocks standing in either parallel or transverse position in true vertical alignment with the webs and shells of the blocks above and below.

5. In a building construction, the combination of wall blocks having three longitudinal voids, the central void being narrow and defined by parallel vertical webs separated the distance of an ordinary mortar joint, column load-bearing blocks consisting of parallel vertical webs and shells and having a narrow central void, said column blocks standing parallel and transversely to the wall blocks and interbonding therewith and each having all its webs and shells in true vertical alignment with the blocks above and below, said column blocks serving to close the ends of the voids of the adjacent wall blocks in the same course and completing each course uniformly.

6. In a wall and pilaster construction, the combination of wall blocks having three longitudinal voids, and hollow pilaster blocks having webs and shells and being of the same height as the three void blocks, and of a length equal to the width of the three void blocks, and having central webs spaced to define a void corresponding to the central void of the three void blocks, and having cross webs defining a plurality of voids between said webs and shells whereby a mortar-carrying bed of substantial area is provided, said pilaster blocks being arranged both parallel and transversely to the wall blocks and interbonding therewith and each having its webs and shells in true vertical alignment with the webs and shells of the wall blocks or pilaster blocks above and below.

FREDERICK HEATH.
